UNITED STATES PATENT OFFICE

JOHAN A. ANDERSON, OF CRANSTON, RHODE ISLAND, ASSIGNOR TO UNIVERSAL WINDING COMPANY, OF BOSTON, MASSACHUSETTS, A CORPORATION OF MASSACHUSETTS

WINDING MACHINE

Application filed May 29, 1928. Serial No. 281,571.

This invention relates to improvements in winding machines and particularly to machines for winding so-called "splicer" bobbins of silk, rayon and other similar materials for use in knitting machines. The improvements are also applicable to other types of winders for winding bobbins and cops having the yarn or other strand material laid in a tapered or inclined chase; that is, bobbins of generally cylindrical form wound with conical chases and tapered or pointed at the nose or delivering end.

10. Another object of the invention is to provide a winding machine in which the thread-guide is maintained in close proximity with the tapered chase on which the winding is being performed while being held away or out of contact with the surface of the winding so as to avoid any chafing action on

15. the yarn or other material.

Another object of the invention is to provide a winding machine having a reciprocating thread-guide for winding the yarn with a predetermined length of traverse in conical or tapered chases and adapted to advance longitudinally with respect to the winding-spindle as the layers of winding are deposited in place, with the delivering part of the guide traversing in a path inclined to

20. the axis of the winding-spindle and controlled in its traverse to hold it away from the surface of the winding.

Another object of the invention is to provide a winding machine of the type specified

25. having means for adjusting the controlling means for the thread-guide in accordance with the taper of the surface on which the winding is being performed as regulated by the size and shape of the bobbin.

Another object of the invention is to provide a winding machine of the type specified in which the thread-guide controlling means is operated directly from the traversing means to effect a control of the guide in synchrony with its traversing motion.

Another object of the invention is to provide controlling means for the thread-guide of the winding machine which is simple in

30. construction, efficient in action and proof

against wear on or derangement of the mechanism.

Further objects of the improvement are set forth in the following specification which describes a preferred form of construction 55 of the invention, by way of example only, as illustrated by the accompanying drawings. In the drawings:

Fig. 1 is an end view of a winding machine showing the present improved thread-guide 60 controlling means applied to use thereon;

Fig. 2 is a front elevation of the winding machine;

Fig. 3 is an enlarged detailed view of the traverse-frame or mounting for the thread-guide of the winding machine showing the controlling means connected to operate the thread-guide;

Fig. 4 is a detailed plan view of the thread-guide showing it in combination with the contact-wheel which feeds the guide progressively along the winding-spindle;

Fig. 5 is a perspective view showing the oscillatable track or frame which actuates the thread-guide to cause it to follow the inclined or conical face of the winding and to hold its guiding part in spaced relation thereto;

Fig. 6 is a cross-sectional view through the traverse-frame showing the slide which connects the cam to reciprocate the traverse-rod; and

Fig. 7 is a plan view of the detent-arm and locking-member which are releasably engaged to hold the traverse-frame in operative relation with respect to the winding-spindle.

In the present drawings the invention is illustrated as applied to use on a winding machine of well-known type comprising the essential elements of a rotating winding-spindle, a traversing thread-guide, a traverse-frame for supporting the thread-guide to adapt it to be reciprocated longitudinally of the winding-spindle, and a rotary cam for reciprocating the thread-guide. In Figs. 1 and 2 of the drawings, 2 designates the box-like frame on which the various elements of the winding mechanism are mounted and 3 is the rotatable winding-spindle

journalled in suitable bearings 4 at the top of the frame. Journalled in bearings 5 on the sides of the frame 2 is a cam-shaft 6 extending parallel with the winding-spindle 3 and carrying the rotating cam 7. The winding-spindle 3 and cam-shaft 6 are connected to be driven from any suitable source of power, these connections not being herein shown or described as they may be of usual 10 construction as well known to those versed in the art. Usually the winding-spindle is driven from a countershaft or motor and the cam-shaft connected rotatively therewith through the means of belts, gears or other instrumentalities providing for the proper ratio of speed between the two shafts.

The winding-spindle 3 overhangs its bearings at one end of the frame 2 and is provided with a suitable holder or mandrel for supporting the bobbin-receiver or tube C on which the winding is performed. As herein shown the winding-spindle 3 carries an enlarged conical boss or support 8 for receiving the tapered or conical butt end c' of the 20 per bobbin-receiver or tube C, and projecting forwardly therefrom is an enlarged cylindrical mandrel 9 which receives the tubular portion c of the bobbin tube or receiver C. Suitable means, not herein shown, are 30 provided for securing the bobbin tube or receiver in place on the mandrel of the winding-spindle to hold it rotatively therewith.

The traverse-frame 10 which supports the thread-guide to reciprocate longitudinally 35 of the winding-spindle 3 is constructed with a horizontal cross-member 11 having opposite depending arms 12 and 13 formed with hubs 14 and 15. The hubs 14 and 15 are mounted to hinge on bushings 16 fixedly held in the 40 bearings 5 on the frame 2 in which the cam-shaft 6 is journalled to rotate. A longitudinally-extending groove 17 in the cross-member 11 of the traverse-frame 10 provides a horizontal trackway for a slidable rod 18. 45 One end of the rod 18 is connected to a cross-head or slide 19 which carries a stud or roller 20 engaging in the helical groove 21 of the cam 7. It will be understood that the cam 7 is secured fast on the cam-shaft 6 and the 50 rotation of the latter turns the cam to reciprocate the slide 19 and rod 18. The opposite or forward end of the rod 18 carries an upright arm 23 connected to a parallel sliding rod 24 which constitutes the traverse-bar for 55 reciprocating the thread-guide 25. As shown in the present drawings, the traverse-bar 24 is mounted to slide in bearings 26 and 27 on a supplemental frame 28 attached to an overhanging portion 29 of the main traverse-frame 10. Referring particularly to Figs. 2 and 3, the supplemental frame 28 is constructed with a rail or bar 30 clamped to an upstanding flange 31 on the overhanging portion 29 of the traverse-frame 10 by means of 60 screws 32. The lower edge of the rail 30

overhangs the groove 17 in the cross-bar 11 of the traverse-frame 10 and is formed with an arcuate bearing face abutting the side of the rod 18 to hold the latter in place in the groove, see Fig. 3.

The traverse-frame 10, as before stated, is swiveled to swing on the axis of the cam-shaft 6, being mounted to adapt it for adjustment to set the traverse-bar 24 in proper relation with respect to the axis of the winding-spindle 3, this adjustment being altered for winding bobbins of different diameter as hereinafter more fully explained. The traverse-frame 10 is normally held in fixed position by means of a detent lock shown in detail in Fig. 3. Referring to Fig. 2, a horizontal rod 33 extends through the side of the forward arm 12 of the traverse-frame 10 and is supported in a lug 34 at the end of the traverse-frame extension 29 and also in a lug 35 at the outer end of the supplementary frame 28. The rod 33 is rotatable in its bearings and carries a weighted detent-arm 36 secured in place thereon by means of a setscrew 37. The detent-arm 36 is formed on one side with a detent lug or latch 38 which is engageable with a shoulder 39 on a fixed locking-member 40, see Fig. 3. The locking-member 40 is of arcuate form and provided with a slot 41 for receiving a bolt 42 by means of which the lock is fixedly clamped to the side of the frame 2. The locking-member 40

may be adjusted in position by loosening its bolt 42 so as to set the detent-shoulder 39 to hold the traverse-frame in fixed position with the traverse-bar 24 in proper relation to the winding-spindle 3. The lug or latch 38 on the detent-arm 36 may be released from the detent-shoulder 39 by rocking the arm 36 through the means of the rod 33, this release of the detents being effected automatically when the winding of a bobbin is completed whereby to permit the traverse-frame 10 to swing away from the winding-spindle so that the bobbin may be more readily doffed therefrom. As herein shown the rod 33 carries an upright lever 43, see Fig. 2, which has an inclined upper end 44 adapted to be engaged by the thread-guide 25 to rock the rod to release the detents. The lever 43 may be adjusted longitudinally of the rod 33 to cause it to be engaged by the thread-guide 25 when the latter has been moved outwardly on the traverse-bar 24 to a predetermined extent in winding a bobbin of the required length.

As before stated, the traverse-bar 24 is mounted to slide in the frame 28 and, as shown in Fig. 2, the rod passes through bushings 47 driven into the bearings 26 and 27 on the frame. At the outer end of the frame 28 the bearing 26 is extended to provide a guard for the end of the bar as it slides to its extreme of traverse. Referring to Fig. 3, the arm 23 which connects the traverse-bar 24 with the lower rod 18 has an offset portion 48

130

fixedly held in a slot in the rod. At its upper end the arm 23 is bent around to encompass the traverse-bar 24 and is clamped thereto by means of a screw 49. Referring to Fig. 4, the traverse-bar 24 is of usual construction having screw threads 50 cut into its side in eccentric relation to its axis. The screw threads 50 are adapted to engage corresponding threads on the interior of a cylindrical nut or sleeve 51 which is rotated to advance the thread-guide 25 longitudinally of the traverse-bar 24. The sleeve or nut 51 extends between and is straddled by the legs 52 and 53 of a bifurcated thread-guide holder 55, the ends of the legs being provided with bearings 56 and 57 swiveled on the bar 24 to adapt the holder to oscillate about its axis. The thread-guide proper may be constituted by a grooved porcelain roll 58 secured to the outer end of the holder 55 by means of a screw or stud 59.

Fixedly secured on the sleeve or nut 51 is a flanged disk 60, to the side of which is attached a contact-wheel 61. The contact-wheel 61 has a flanged peripheral rim adapted to make contact with the surface of the winding on the bobbin whereby to turn the nut 51 on the bar 24. The periphery of the contact-wheel 61 makes contact with the base of the conical chase of the winding at each rearward stroke of the thread-guide 25 and is thereby rotated to a slight extent to turn the nut 51 to feed the guide progressively outward along the traverse-bar 24. The threaded bore of the nut 51 is of larger diameter than the bar 24 so that it may be moved laterally to disengage its threads from the threads on the bar when it is required to release the nut to return the thread-guide 25 to first position at the start of the winding. The nut 51 is normally held in eccentric relation with respect to the axis of the bar 24, to maintain engagement between the threads on the bar and nut, by means of a spring 62. The spring 62 has a coiled portion 63 with an arm 64 reaching outwardly therefrom and bearing against the rim of the disk 60 on the nut 51. The construction and arrangement of these parts is substantially the same as usually employed on bobbin and cop winding machines in which the thread-guide is advanced longitudinally of the winding-spindle to deposit the yarn in forwardly-stepped courses laid on an inclined or conical chase.

As the thread-guide 25 is reciprocated longitudinally of the winding-spindle 3 the thread-guide holder or arm 55 oscillates about the axis of the traverse-bar 24 to adapt the feeding part of the guide to follow up and down the inclined chase of the bobbin being wound. In previously used bobbin winding machines of this type the thread-guide is arranged to bear against the surface of the winding to direct its course up and down the inclined chase. It has been found, however,

that when certain materials such as silk, rayon and other delicate filaments are being wound the contact of the guide with the surface of the winding causes a chafing and abrasive action which has a deleterious effect on the material. That is to say, the rubbing action of the guide on the bobbin chafes and roughens the material and spoils the finish of the yarn. It is one object of the present improvement to avoid this chafing or abrasive action of the guide on the material and to this end means are provided for controlling the movement of the thread-guide to cause it to follow the chase of the bobbin without contact thereon. In the present form of construction of the invention the means for controlling the action of the guide for this purpose consists of positively driven mechanism for oscillating the thread-guide holder 55 on the traverse-bar 24 during the reciprocatory motion of the guide. The guide-controlling means is operated synchronously with the guide-traversing means and a preferred form of construction of the mechanism will next be described.

Referring to Figs. 1, 2 and 3, the thread-guide controlling means comprise a rockable guiding-track 65, preferably constructed in the form of a sheet-metal yoke or bifurcated frame as illustrated in perspective view in Fig. 5. The frame 65 is constituted by a longitudinal rail or track 66, preferably of angle-iron shape in cross section with laterally-extending arms 67 at its ends. The arms 67 are provided with holes 68 whereby the frame 65 may be rockably mounted on the bushings 47 which project from the bearings 26 and 27 on the supplemental traverse-frame 28. As shown most clearly in Figs. 3 and 4, the leg 53 of the bifurcated thread-guide holder 55 is provided with an extension or arm 69 which is folded over at its end to provide a double-sided shoe or slide 70 adapted to straddle the upper side of the angularly shaped track 66. Through this means the thread-guide 25 is connected to be moved by and with the oscillatable frame 65 during the reciprocation of the guide and as it feeds outward along the traverse-bar 24 with the shoe 70 sliding on the track 66.

As one means for actuating the controlling means in synchrony with the traversing movement of the thread-guide, Figs. 1 and 3 illustrate the frame 65 connected to be oscillated from a crank or eccentric rotated from the cam-shaft 6. In the present preferred form of construction the cam-shaft 6 carries a wheel 71 fixedly attached to its end by means of the stud or screw 72, see Fig. 2, and formed on its outer side with a central hub or boss 73. Secured to the face of the boss 73 is a circular plate or disk 74 carrying a crank-pin 75. The disk 74 is preferably adjustable in eccentric relation with respect to the axis of the cam-shaft 6 to vary the throw of the

crank-pin 75 whereby to alter its range of action. For this purpose the disk 74 is formed with a radial slot 76 for receiving the screw 77 which clamps it to the face of the 5 boss 73 on the wheel 71.

The crank or eccentric 74 is connected to oscillate the frame 65 by means of a link or connecting-rod 78. As herein shown the link 78 comprises two sections 79 and 80 which are 10 slidable on each other to adjust the length of the connection in accordance with the adjustment of the crank-pin 75 and also to properly set the thread-guide in spaced relation with respect to the surface of the winding on different types and sizes of bobbins. One section 79 of the link 78 has its end bent around 15 in a loop 81 engaging around the crank-pin 75, and the other section 80 has a similar loop 82 connected by a pin 83 to a bifurcated member or yoke 84 which is fixedly attached to the back of the track 66. The two sections 79 and 20 80 are held together by strap-like clamps 85 enclosing their overlapped portions, the clamps being provided with thumb-screws 86 25 adapted to bind against the parts to lock them in adjusted relation. By releasing the screws 86 the two sections 79 and 80 of the connecting-rod 78 may be slid one on the other to shorten or extend its length.

30 The method of operation of the machine in winding a bobbin is as follows: The paper tube or other bobbin-receiver C is placed on the mandrel 9 of the winding-spindle 3 and the end of the yarn or other strand material 35 leading from its source of supply, not herein shown, is attached to the tube in any suitable manner. The strand y may lead from below or, as shown in the present drawings, it may draw downwardly from a supply placed 40 above the machine, being carried around the porcelain roll 58 to feed therefrom to the surface on which the winding is performed.

Prior to the commencement of the winding operation the traverse-frame 10 is set in the 45 position illustrated in Figs. 1 and 3 with the detent-lug 38 on the latch 36 engaged with the shoulder 39 on the locking-member 40 to hold the frame in fixed relation. The thread-guide 25 is initially carried back toward the 50 rearward end of the traverse-bar 24 to start the winding at the base of the bobbin, the setting of the guide being accomplished by releasing the nut 51 from the threads on the bar in the manner as previously explained.

55 The thread-guide 25 is thus adjusted to starting position with its contact-wheel 61 at a point opposite the large end of the conical butt c' of the bobbin-receiver C to adapt it to contact with the yarn as it winds thereon, 60 see Fig. 3. The eccentric plate or disk 74 is adjusted to regulate the throw of its crank-pin 75 to impart an oscillating motion to the frame 65 sufficient to rock the thread-guide 25 between the positions illustrated in 65 full and dash lines in Fig. 3.

The link or connecting-rod 78 is adjusted to regulate the position of the frame 65 so that when it is rocked downwardly to the full extent as shown by the full lines in Fig. 3 the roll 58 of the thread-guide 25 will just clear the rim of the butt of the carrier C. In other words, the adjustment of the eccentric 74 and the connecting-rod 78 is such as to provide for the proper extent of oscillation of the thread-guide 25 and to also control its operative relation with respect to the surface on which the winding is performed to insure that as it travels up and down the incline it will be prevented from contacting with the yarn being laid on the inclined chase. 70 75

The machine is started to operate through the shifting of a clutch or other suitable instrumentalities controlled by a starting-lever or handle 90 shown in Figs. 1 and 2. As the machine begins to operate the winding-spindle 3 is rotated to turn the bobbin-receiver C, and the cam 7 is driven to impart reciprocation to the sliding rod 18. The rod 18 is thus caused to reciprocate the traverse-bar 24 connected therewith by means of the arm 23. 80 The reciprocation of the traverse-bar 24 traverses the thread-guide 25 back and forth longitudinally of the winding-spindle 3 with its extent of traverse regulated by the throw of the cam 7 which is proportioned to the length 85 of chase to be wound. At the start of the winding the thread-guide 25 will be traversed between the base end of the conical butt c' of the carrier C and the apex end thereof to deposit the strand material in helical coils 90 thereon. As the guide travels forward from the base end of the butt c' the turning of the cam-shaft 6 rotates the eccentric 74 to rock the frame 65 upwardly to the position indicated by the dash lines in Fig. 3. This rocking action of the frame 65 causes a corresponding oscillation of the thread-guide arm 55 to carry the porcelain roll 58 inwardly towards the axis of the bobbin, and in this way the delivering portion of the guide is caused 100 to travel down the incline, or in other words to follow the conical chase so that it is maintained close to the surface on which the winding is being formed to properly direct the strand thereto. As the thread-guide reaches 105 the forward end of its traverse the crank-pin 75 on the disk 74 crosses dead center, whereupon it will impart a reverse motion to the frame 65 to rock the thread-guide roll 58 outwardly or back to the position indicated 110 by the full lines in Fig. 3. In this manner the oscillating movement of the thread-guide is synchronized with its longitudinal traversing motion so that the roll 58 will invariably follow the inclined surface of the winding without bearing thereagainst. 115 120 125

As the strand material is deposited on the conical butt c' of the receiver C it will be built up in a layer of crossing turns or coils and eventually, at the rearward stroke of the

thread-guide 25, the contact-wheel 61 will be engaged by the winding as indicated in Figs. 1 and 3. During this brief engagement the contact-wheel 61 is rotated to a slight extent to feed the nut 51 along the traverse-bar 24 to advance the thread-guide towards the tip end of the bobbin. In this way the bobbin is built up in a series of overlying courses of coils which advance progressively 10 along the axis of the receiver C to form the bobbin with a cylindrical body and tapered or conical nose-end as indicated by the dot-and-dash lines in Fig. 2. As the thread-guide 25 feeds outwardly along the traverse-bar 24 the shoe 70 on the guide-holder 55 slides along the track 66 to maintain the connection between these parts. After the thread-guide 25 has been fed along the traverse-bar 24 to an extent sufficient to complete 20 the bobbin to the required length, finally, at the outward traverse of the guide, the leg 52 of its holder 55 will make contact with the inclined end of the arm or lever 43 to rock the rod 33. The rocking of the rod 33 releases the detent-latch 36 from the locking-member 40, whereby the traverse-frame 10 is caused to swing back to remove the contact-wheel 61 from contact with the winding. At this juncture suitable instrumentalities, not 30 herein illustrated, are brought into action to disconnect the drive of the machine to arrest the winding operation so that the completed bobbin may be doffed from the winding-spindle 3 and a new tube or receiver placed 35 thereon.

It will be observed that the present improvement provides a simple yet highly efficient means for controlling the operation of the thread-guide to maintain it in close proximity to the tapered chase on which the winding is being performed, while preventing it from bearing against the surface of the winding to chafe or abrade the strand material. The controlling mechanism for the guide 40 may be adjusted in accordance with the shape and dimensions of the bobbin being wound without disturbing the synchrony of operation between the traversing motion of the guide and its oscillating action.

While I have herein described and illustrated the improvement as applied to use with a certain type of winding machine and as embodied in a preferred form of construction, it is to be noted that various modifications 50 may be made in the method of applying the device to use and in the structure and arrangement of its parts without departing from the spirit or scope of the invention. Therefore, without limiting myself in this 55 respect, I claim:

1. In a winding machine, the combination of a winding-spindle, an oscillating thread-guide for traversing strand material on the winding-spindle to deposit it in inclined 60 chases to form a bobbin, an oscillatory track

along which the thread-guide travels during the winding of the bobbin, and means to oscillate the track to cause the thread-guide to follow the inclined chase of the bobbin without contact therewith.

2. In a winding machine, the combination of a winding-spindle, an oscillating thread-guide for guiding strand material to wind a bobbin on the spindle, means for effecting a relative traverse between the winding-spindle and thread-guide, an oscillatory track along which the thread-guide travels during the winding of the bobbin, and means to oscillate said track to cause the thread-guide to follow the inclined chase of the bobbin without contact therewith.

3. In a winding machine, the combination of a winding-spindle, a thread-guide for feeding strand material to the winding-spindle to wind a cop or bobbin thereon, means for effecting a relative traverse between the winding-spindle and thread-guide, and means actuated from a going part of the machine to oscillate the thread-guide to cause it to move toward and away from the winding-spindle during the traverse to follow the incline of the conical chase of the bobbin being wound without contact therewith.

4. In a winding machine, the combination of a winding-spindle, a thread-guide for feeding strand material to the winding-spindle to wind a bobbin thereon, means for effecting a relative traverse between the winding-spindle and thread-guide, and means outside of the control of the bobbin and positively actuated from the traversing means to cause the guide to move toward and away from the axis of the winding-spindle to follow the inclined chase of the bobbin without contact therewith.

5. In a winding machine, the combination of a winding-spindle, a thread-guide for feeding strand material to the winding-spindle to wind a bobbin thereon, means for traversing the thread-guide longitudinally of the winding-spindle, and means actuated from a going part of the machine to oscillate the thread-guide toward and away from the axis of the winding-spindle in synchrony with its traversing motion to cause it to follow the inclined chase on the bobbin without contact therewith.

6. In a winding-machine, the combination of a winding-spindle, a thread-guide for traversing strand material on the spindle to wind a bobbin, means to advance the thread-guide along the winding-spindle to build the bobbin in progressively advancing courses, and means actuated from a going part of the machine to oscillate the thread-guide toward and away from the axis of the winding-spindle during its traversing motion to cause it to follow the inclined chase of the bobbin without contact therewith.

7. In a winding machine, the combina- 130

- tion of a winding-spindle, a thread-guide for feeding strand material to the winding-spindle to wind a bobbin thereon, means for effecting a relative traverse between the winding-spindle and thread-guide, controlling means connected with the thread-guide, and means actuated from a going part of the machine to oscillate said controlling means to cause the thread-guide to move toward and away from the axis of the winding-spindle during the traverse to follow the inclined chase of the bobbin without contact therewith.
8. In a winding machine, the combination of a winding-spindle, a thread-guide for feeding strand material to the winding-spindle to wind a bobbin, means for traversing the thread-guide longitudinally of the winding-spindle, means for mounting the thread-guide to adapt it to move toward and away from the axis of the winding-spindle during its traverse with respect thereto, and means actuated from a going part of the machine to positively oscillate the thread-guide to cause it to follow the inclined chase of the bobbin without contact therewith.
9. In a winding machine, the combination of a winding-spindle, a reciprocating traverse-bar, a thread-guide swiveled on the traverse-bar, means to reciprocate the traverse-bar to cause the thread-guide to traverse strand material to wind a bobbin on the winding-spindle, and means actuated from a going part of the machine to positively oscillate the thread-guide on the traverse-bar to cause it to follow the inclined chase of the bobbin without contact therewith as it feeds the yarn thereto.
10. In a winding machine, the combination of a winding-spindle, a traverse-bar extending opposite the winding-spindle, a thread-guide swiveled on the traverse-bar to adapt it to swing toward and away from the axis of the winding-spindle, means for reciprocating the traverse-bar to cause the thread-guide to traverse strand material on the winding-spindle to wind a bobbin, and means for positively rocking the thread-guide toward and away from the winding-spindle at each traverse thereof in the manner and for the purpose substantially as specified.
11. In a winding machine, the combination of a winding-spindle, a thread-guide for traversing strand material on the winding-spindle to wind a bobbin, means for reciprocating the thread-guide, a rockable member connected with the thread-guide, and means actuated from a going part of the machine to rock said member to oscillate the thread-guide toward and away from the axis of the winding-spindle during its reciprocation to cause it to follow the inclined chase of the bobbin without contact therewith.
12. In a winding machine, the combination of a winding-spindle, a traverse-bar, a thread-guide swiveled on the traverse-bar, means to reciprocate the traverse-bar to cause the thread-guide to traverse the yarn to wind a bobbin on the winding-spindle, a rockable track, means connecting the thread-guide to the track and slidably thereon, and means to rock the track to oscillate the thread-guide during its traverse to cause it to follow the inclined chase of the bobbin without contact therewith.
13. In a winding machine, the combination of a winding-spindle, a reciprocable traverse-bar, a thread-guide swiveled on said traverse-bar and adapted to be progressively fed therewith, means to reciprocate the traverse-bar, a track swiveled to rock on the traverse-bar, a slide on the thread-guide slidably on the track, and means for rocking the track to oscillate the thread-guide to cause it to follow the inclined chase of the bobbin without contact therewith.
14. In a winding machine, the combination of a winding-spindle, a thread-guide for feeding strand material to the winding-spindle to wind a bobbin, means for effecting a relative traverse between the winding-spindle and thread-guide, means for oscillating the thread-guide to cause it to follow the inclined chase of the bobbin during the traverse of the yarn thereon, and an eccentric for operating the oscillating-means.
15. In a winding machine, the combination of a winding-spindle, a thread-guide for feeding strand material to the winding-spindle to wind a bobbin, means for effecting a relative traverse between the winding-spindle and thread-guide, an eccentric rotated from the traversing means, and means connecting the eccentric to oscillate the thread-guide toward and away from the axis of the winding-spindle to cause it to follow the inclined chase of the bobbin during the traverse of the strand material thereon.
16. In a winding machine, the combination of a winding-spindle, a thread-guide adapted to be traversed longitudinally of the winding-spindle, a cam for traversing the thread-guide, means for oscillating the thread-guide toward and away from the axis of the winding-spindle during its traverse, an eccentric rotated with the cam, and means connecting the eccentric to operate the oscillating-means to cause the thread-guide to follow the inclined chase of the bobbin during its traverse in relation thereto.
17. In a winding machine, the combination of a winding-spindle, a traverse-bar, a thread-guide swiveled on the traverse-bar to adapt it to swing toward and away from the axis of the winding-spindle, a frame swiveled on the traverse-bar and provided with

a guiding-track arranged parallel therewith, a slide on the thread-guide slidable on the track, and means for oscillating the frame to rock the thread-guide toward and away from the winding-spindle during its traverse with respect thereto.

18. In a winding machine, the combination of a winding-spindle, a traverse-bar extending parallel therewith, a thread-guide swiveled on the traverse-bar, a contact-wheel adapted to be turned by contact with the bobbin to feed the thread-guide along the traverse-bar, a frame swiveled to rock on the traverse-bar and provided with a longitudinal track extending parallel therewith, a slide on the thread-guide slidable on the track, and means for rocking the frame in synchrony with the reciprocation of the traverse-bar.

19. In a winding machine, the combination of a winding-spindle, a cam-shaft, a cam on said shaft, a traverse-bar reciprocable longitudinally of the winding-spindle, means connecting the cam to reciprocate the traverse-bar, a thread-guide swiveled on the traverse-bar to adapt it to swing toward and away from the axis of the winding-spindle, a track mounted to rock with respect to the traverse-bar, means for slidably connecting the thread-guide with the track, an eccentric on the cam-shaft, and a connecting-rod connecting the eccentric to rock the track to oscillate the thread-guide at each reciprocation thereof.

20. In a winding machine, the combination of a winding-spindle, a cam-shaft extending parallel therewith, a traverse-frame, supported from the cam-shaft, a cam rotated from the cam-shaft, a traverse-bar reciprocable in the traverse-frame, means connecting the cam to reciprocate the traverse-bar, a thread-guide swiveled to rock on the traverse-bar, a rockable frame having a guiding-track, means on the thread-guide in sliding engagement with the track, an eccentric rotated from the cam-shaft, and an adjustable connecting-rod connecting the eccentric to oscillate the frame.

In testimony whereof I hereunto affix my signature.

JOHAN A. ANDERSON.
